SLUG CASTING MACHINE

John H. Hilpman, Hollis, N. Y., assignor to Mergenthaler Linotype Company, a corporation of New York

Application July 14, 1934, Serial No. 735,156

11 Claims. (Cl. 199—32)

This invention relates to typographical machines, such as linotype machines of the general organization represented in U. S. Letters Patent to O. Mergenthaler No. 436,532, wherein circulating matrices are released from a magazine in the order in which their characters are to appear in print, then assembled in line, the composed line transferred to the face of a slotted mold, the mold filled with molten metal to form a slug or linotype 5 against the matrices which produce the type characters thereon, and the matrices thereafter returned through distributing mechanism to the magazine from which they started. In these machines, the composed line is transferred from 10 the assembling channel or elevator into the casting channel or elevator by means of a horizontally movable carriage comprising a slide or body portion and a pair of line engaging fingers, one short and the other long. The short right-hand 15 finger is fixed to the carriage slide, while the long left-hand finger is loosely mounted with reference thereto, the latter finger being ordinarily provided with a friction device which tends to hold it stationary. As the transfer carriage is thus constructed, the composed line is advanced to the 20 left by the right-hand finger and in its advance picks up the left-hand finger and carries it along therewith, it being understood that the frictional resistance offered to the movement of the left-hand finger is overcome by the power applied 25 (usually by a heavy spring) to operate the carriage. In the return movement of the carriage, the left-hand finger is restored to the right by the customary adjustable stop on the carriage slide 30 which locates it at the proper distance from the right-hand finger. The loose mounting of the left-hand finger is intended primarily to enable the transfer carriage to accommodate itself to short lines, that is to say, lines shorter than 35 that for which the two fingers are adjusted. Thus, when a short line is delivered to the transfer carriage, the leading matrix of the line necessarily stands some distance away from the left-hand finger, but this distance is immediately taken 40 up during the initial movement of the transfer carriage, due to the fact that the left-hand finger is held at rest until picked up by the advancing line. In this way, the two fingers are caused to approach each other and confine the line between them, reliance being placed upon the above 45 mentioned friction device to maintain the fingers in this condition until the line is taken from the carriage by the casting elevator.

It has been found in practice that, notwithstanding the friction device carried thereby, the

left-hand finger frequently becomes separated from the line before the latter leaves the transfer carriage, such separation being due for the most part to the jar developed by the abrupt stoppage of the carriage which sometimes occurs during its line transfer movement. For example, there are times when a second line is transferred from the assembling elevator before the machine has completed its cycle of operation, and the transfer carriage under such conditions 10 is abruptly stopped in a waiting position in the intermediate channel. As a result, the matrices become loose in the line (particularly those at the leading end) and oftentimes drop out or else become so displaced as to interfere with the 15 proper delivery of the line to the casting and other devices, thereby causing damage to the parts and giving rise to other serious objections. Moreover, it may happen that the left-hand finger will be thrown into the path of the casting 20 elevator as it descends from its upper transfer level to line receiving level, causing even greater damage to the parts.

The present invention is intended to overcome the foregoing objections and aims specifically to 25 provide an effective guard against an abrupt stopping of the line transfer carriage in its waiting position. To this end, the dash-pot which is ordinarily provided for resisting the action of the spring which moves the line transfer carriage 30 in its delivery stroke has been modified in such manner as to offer momentarily a greater resistance to the actuating spring just before the carriage reaches its waiting position.

In the accompanying drawings, the invention 35 has been shown merely in preferred form and by way of example and as applied to the particular kind of machine mentioned, but obviously many changes and alterations may be made therein and in its mode of application and still be comprised within its spirit. Generally speaking, the invention is not limited to any specific form or adaptation except insofar as such limitations are specified in the claims.

Referring to the drawings:

Fig. 1 is a front elevation of a portion of a linotype machine equipped with the present improvement;

Fig. 2 is a similar view, on an enlarged scale, of the line transfer carriage and associated parts;

Fig. 3 is a section taken on the line 3—3 of Fig. 2;

Fig. 4 is a section taken on the line 4—4 of Fig. 3; and

Fig. 5 is a transverse sectional view of the assembling elevator.

In the drawings, only those parts of the machine necessary to an understanding of the invention have been illustrated, and it will be understood that the other parts may be of the ordinary or any suitable construction.

The matrices S are released from the magazine in which they are stored by the usual keyboard 10 and drop onto the conveyor belt A which delivers them to the assembling elevator A¹, wherein they are composed in line with the expansible spacebands T. After composition, the elevator A¹ is raised into registration with the intermediate 15 channel B and the composed line then carried therethrough into the casting elevator C, which thereupon descends to present the line to the slug casting mold. The shifting of the composed line from the assembling elevator A¹ to the casting elevator C is effected by a so-called line transfer carriage comprising the horizontal slide D and the two line engaging fingers D¹ and D². The slide D is mounted in the guideway E¹ of the machine frame E and is moved to and fro 20 by the power-operated lever F¹. The right-hand finger D¹ is rigidly secured to the slide D, whereas the left-hand finger D² is loosely mounted with reference thereto, being attached to a separate block (not shown) slidably arranged in the guideway E¹. The setting of the finger D² from the finger D¹ is determined by an adjustable stop D³ carried by the slide and which is adapted to abut 25 against the block on which the finger is mounted in the line receiving position of the transfer carriage (see Fig. 1). The stop D³ is held in its adjusted position by the pawl D⁴ which cooperates with ratchet teeth formed on the front face of the slide D. The finger D², or more specifically the block to which it is fixed, is provided with a friction device in the form of the spring-pressed 30 plunger D⁵ bearing against a smooth faced portion of the machine frame just above the guideway E¹.

As before outlined, the assembling elevator A¹ is raised to introduce the composed line between the fingers D¹, D² of the transfer carriage. As it reaches its uppermost position, the elevator A¹ trips a catch to release the carriage and thus permit it to convey the line through the intermediate 45 channel B to the casting elevator C. The slide D is connected by the link F to the actuating lever F¹ which is mounted upon the rock shaft F² also carrying the arm F³ connected to the spring F⁴ which supplies the power to move the transfer carriage. The rock shaft F², in addition, carries the arm F⁵ bearing the roller F⁶ for 50 engaging the cam G¹ mounted on the main cam shaft of the machine, the cam operating through the arm F⁵ to rock the shaft F² against the action 55 of the spring F⁴ to return the carriage to its normal position.

When the carriage is released and the spring F⁴ permitted to act, the roller F⁶ strikes the starting dog G² carried by the cam G¹ and trips it 60 from engagement with the stop G⁴ to initiate the automatic operation of the machine. However, on occasions when the transfer carriage moves toward delivery position with a composed line before the machine has completed a cycle of operation, the starting dog will not be in a position to be tripped by the roller F⁶ and the latter will be arrested by the edge of the cam G¹, say at a point G³, and thus the transfer carriage will be stopped in a waiting position until the machine's 65 cycle of operation has been completed and the

trip dog G² brought into engagement with the roller F⁶. Of course, it is understood that in this instance the point G³ arbitrarily selected is any point on the cam G¹ which at the time the line is transferred occupies the starting position of the trip dog G² shown in Fig. 1 and that, as the cam G¹ continues to rotate, the roller F⁶ follows the contour of its edge until the trip dog is brought into position to be acted upon by the roller, the transfer carriage during this interval gradually moving toward its final position of delivery by virtue of the shape of the cam and the dog G² instead of being tripped is prevented by the roller F⁶ from engaging the stop G⁴, so that the machine continues without interruption into its 15 second cycle of operation.

The movement of the transfer carriage in its delivery stroke is under the control of the dash-pot M, whose plunger M² is connected by the plunger rod M¹ to the arm F⁷ of the rock shaft 20 F². The plunger M² is provided in its upper wall M⁴ with the one-way valve M⁵ to admit air into the upper portion of the cylinder M³ as the plunger moves downwardly during the return stroke of the transfer carriage, and the plunger 25 carries the washer M⁶ of leather or other suitable material to effect a compression seal as in the case of an ordinary air pump.

The foregoing parts and their mode of operation are substantially the same as those embodied in commercial linotype machines. However, it may be noted that when the transfer carriage is moved to the left for the transfer of the composed line, the left-hand finger D² is held at rest by its spring-pressed plunger D⁵ until the forward end of the line is carried against it by the advance of the right-hand finger D¹ (compare Figs. 1 and 2), the matrices and spacebands up to this time being held against displacement in the assembling elevator by the resilient rails A² which engage the upper ears of the matrices (see Fig. 5). The power applied by the spring F⁴ to advance the carriage is sufficient, of course, to overcome the slight frictional resistance of the plunger D⁵ and, consequently, the finger D² is 45 carried along by the composed line until the carriage reaches its final position of delivery, where it is arrested by the engagement of the slide D with a fixed stop E² on the machine frame. If, as shown, the line forwarded is 50 shorter than the original distance between the two fingers, the left-hand finger D² will stand to the right out of engagement with its setting stop D³ at the time of arrest of the transfer carriage in either of the aforesaid positions and, 55 hence, the finger has a tendency to jump or rebound away from the line when the carriage is arrested. However, even with the dash-pot M to steady the movement of the carriage, the jar developed by the abrupt stoppage of the carriage 60 in its waiting position is severe enough to effect this jumping of the finger and give rise to the objections previously noted, because the compression of air in the dash-pot is less during the initial rise of the plunger M² than as it approaches the end of its stroke.

According to the present invention, the action of the dash-pot has been modified, so that just prior to the time when the roller F⁶ would engage the edge of the cam G¹ and arrest the carriage in its waiting position if the line were transferred prematurely, it (the dash-pot) automatically operates momentarily to offer more resistance and thereby brake the carriage and slacken its speed.

- In the preferred embodiment illustrated, there is fixed in the upper wall M^4 of the dash-pot plunger M^2 a piston valve M^7 , having flattened portions M^8 and an unflattened portion or lobe M^9 . The piston M^7 passes through a bore or bushing M^{10} in the cylinder head M^{11} , the bore being of slightly larger diameter than the piston so that the latter may slide freely therethrough. The cylinder head M^{11} is also formed with a port M^{12} through which air is taken into and exhausted from the cylinder; and an adjustable cover or cap M^{13} is provided to more or less obstruct the port, as desired, and vary the flow of air therethrough.
- In the operation of the machine, when the transfer carriage is in its line receiving position (see Fig. 1), the plunger M^2 of the dash-pot M occupies its lowermost position with its top surface at the level x in Fig. 3, and the lobe M^9 of the piston valve M^7 occupies a position within the cylinder as indicated by the lower dotted line in Fig. 3. Now, when the transfer carriage is released by the upward movement of the assembling elevator A^1 in delivering the composed line between the fingers D^1 and D^2 and the spring F^4 exercises itself to move the carriage to the left, the plunger M^2 is forced upwardly, compressing the air in the cylinder and thus resisting the action of the spring F^4 so that the carriage moves only as fast as the air is exhausted from the cylinder and permits the plunger to move upwardly, but, as already stated, the compression at this time is not very great. During the initial movement of the plunger, the air is exhausted from the cylinder through the port M^{12} and also through the clearance space presented between the upper flattened portion M^8 of the piston valve M^7 and the bore M^{10} . At about the time the parts have moved sufficiently so that the roller F^6 approaches the position P indicated by the dotted lines in Fig. 1 (just before it would engage with the cam G^1 and be arrested in its waiting position), the lobe M^9 of the piston valve M^7 reaches the lower end of the bore M^{10} . From then on until the lobe M^9 passes through the bore M^{10} and reaches the position shown by the full lines in Fig. 3, when the plunger M^2 is at approximately the level y , the escape of air from within the cylinder in the region of the bore M^{10} is substantially cut off, leaving the port M^{12} as the only exhaust passage. Hence, with the volume of air exhaust thus diminished, the speed of rise of the plunger M^2 is decreased and a greater resistance to the action of the spring F^4 is offered, whereby the speed of the line transfer carriage is momentarily slackened to such extent that there can be no abrupt jarring stop if the roller F^6 should come into engagement with the cam G^1 . Consequently, there is no separating of the left-hand finger D^2 from the composed line, for the spring plunger D^5 is capable of resisting whatever slight separating tendency there may be. To continue with the operation: After the lobe M^9 of the piston valve M^7 has cleared the bore M^{10} , the lower flattened portion M^8 of the valve is presented and the transfer carriage is free as initially to move to delivery position, the plunger M^2 rising to its uppermost position z indicated in Fig. 3.
- It will be noted that the volume of air escaping through the port M^{12} in the cylinder head M^{11} may be regulated by the closure cap M^{13} and this control is for the purpose of regulating the volume of air exhausted from the cylinder in conjunction with the air exhausted through

the bore M^{10} past the flattened portions M^8 of the piston valve M^7 to obtain the desired resistance by the dash-pot M during the initial and final movements of the transfer carriage. It should also be noted that the period of greater resistance for reducing the speed of the transfer carriage may be varied by increasing the length of the lobe M^9 of the piston valve M^7 or the length of the bore M^{10} , or both.

Briefly stated, the dash-pot, modified in the manner shown and described, imposes a braking action upon the line delivery carriage just prior to the time when it reaches its waiting position, thereby avoiding the objections which heretofore have existed because of the abrupt stoppage which necessarily takes place in the absence of such braking action. It will be understood, of course, that when there is no waiting line and, therefore, no waiting position of the transfer carriage, the carriage will be permitted to travel uninterruptedly from line receiving to line delivery position, the resistance offered by the dash-pot being only momentary and never sufficient to cause of itself the arrest of the carriage.

Having thus described my invention, what I claim is:

1. In a typographical machine, the combination of a movable line transfer carriage adapted at times to be arrested in a waiting position, means for operating the carriage, and means for reducing the speed of the carriage at a point in advance of its waiting position.

2. In a typographical machine, the combination of a movable line transfer carriage, means for moving the carriage from line receiving position to line delivery position, and means effective momentarily to slacken the speed of the carriage before it reaches an intermediate waiting position.

3. In a typographical machine, the combination of a movable line transfer carriage, means for moving the carriage from line receiving position to line delivery position, and braking means operative momentarily to slacken the speed of the carriage before it reaches an intermediate waiting position.

4. In a typographical machine, the combination of a movable line transfer carriage, means for moving the carriage, means for arresting the carriage in a waiting position, and braking means operative to slow up the carriage before it is arrested.

5. In a typographical machine, the combination of a movable line transfer carriage adapted at times to be arrested in a waiting position, spring means for operating the carriage, and a dash-pot to resist the action of the spring, said dash-pot being automatically operative momentarily to offer its maximum resistance to the carriage at a point in advance of its waiting position.

6. In a typographical machine, the combination of a movable line transfer carriage, spring means for moving the carriage, and a dual action dash-pot, said dash-pot resisting the action of the spring throughout the travel of the carriage and momentarily offering an increased resistance at an intermediate point of travel to slow up the carriage at that point.

7. In a typographical machine, the combination of a movable line transfer carriage, spring means for moving the carriage, and a dual action dash-pot to resist the action of the spring, said dash-pot acting during the initial and final stages of movement of the carriage to offer a

predetermined resistance to said spring means, and at an intermediate stage operating automatically to offer an increased resistance to slacken the speed of the carriage momentarily.

8. In a typographical machine, the combination of a movable line transfer carriage adapted at times to be arrested in a waiting position, a dash-pot operative to resist the movement of the line transfer carriage, said dash-pot being equipped with an automatic valve operative to increase the resistance offered by the dash-pot at different stages during its operation.

9. In a typographical machine, the combination of a movable line transfer carriage adapted at times to be arrested in a waiting position, a fluid controlled dash-pot for resisting the movement of the line transfer carriage, said dash-pot including a plunger operating within a cylinder and being equipped with a valve controlled by the movement of the plunger and operating during each stroke of the plunger to cause the dash-pot to offer an increased resistance momentarily during its operation.

10. In a typographical machine, the combination of a movable line transfer carriage adapted at times to be arrested in a waiting position, a dash-pot operative to resist the movement of the line transfer carriage, said dash-pot includ-

ing a plunger operating within a cylinder and being equipped with a piston valve movable by the plunger and passing through a bore in the cylinder wall, the valve being formed to present clearance points between it and the wall of the bore at intervals during its movement and being operative to cause the dash-pot to offer increased resistance momentarily during its operation.

11. In a typographical machine, the combination of a movable line transfer carriage adapted at times to be arrested in a waiting position, a dash-pot operative to resist the movement of the line transfer carriage, said dash-pot including a plunger operating within a cylinder and being equipped with a piston valve movable by the plunger and passing through a bore in the cylinder head, the piston being flattened on one side except for a short distance substantially midway of its length, a clearance being presented between the flattened portions of the piston and the bore and the unflattened portion of the piston substantially filling the bore as the piston moves therethrough, whereby the dash-pot offers increased resistance to the carriage when the unflattened portion of the piston passes through the bore.

JOHN H. HILPMAN.
